UNITED STATES PATENT OFFICE.

WILLIAM H. WHITE, OF ROANOKE, VIRGINIA, ASSIGNOR TO GRAHAM-WHITE SANDER CORPORATION, OF ROANOKE, VIRGINIA, A CORPORATION OF VIRGINIA.

LOCOMOTIVE SANDER.

Application filed November 9, 1925. Serial No. 67,931.

The invention relates to sanders for locomotives.

The primary object of the invention, generally stated, is to provide control means whereby sand may be supplied in varying quantities depending upon circumstances, as for instance selectively to one pair of drivers or two pairs thereof.

In Patent No. 1,409,538 granted March 10, 1922 to James Frantz and assigned to the same assignee as the present invention there is disclosed a sanding apparatus including sand traps located on a locomotive boiler near the sand dome and operable by 15 fluid pressure under the control of a valve located within the cab, the valve being of the duplex type and having a control handle movable in one direction for supplying sand in advance of the front drivers and movable in the opposite direction for supplying sand to the rear of the rear drivers as is desirable when backing. In Patent No. 1,521,799 granted to me January 6, 1925 and owned by the same assignee I have disclosed 20 a similar arrangement with the additional feature of the provision of means for sanding the wheels of a booster. Under some circumstances it is desirable to apply sand to the tracks in advance of only one pair 25 of drivers whereas under other conditions where a greater quantity of sand is necessary it is desirable to apply sand in advance of more than one pair of drivers. However, under ordinary systems of control, there is 30 no provision for such an alternative feed.

It is with the above facts in view that I have designed the present invention which has for a more specific object the provision of sanding control means embodying a duplex valve, the arrangement of piping and other details being such that upon movement of the valve handle in one direction compressed air may be supplied to the sand traps for sanding two pairs of drivers, 40 movement in the other direction resulting in feeding compressed air to only the traps for one set of drivers, this selection being under ready control of the engineer and making it possible to economize on sand consumption when only a small quantity is 45 really needed.

It is a further object of the invention to provide an equivalent arrangement of parts in association with the compressed air pipes leading to the cleaners of the sand traps 50

with which the control means is used so that blasts of air will be supplied to the cleaning nozzles of only those sand traps in operation at the particular time as selected by the engineer, both features of the invention acting 60 to economize not only in the matter of sand consumption but also in the use of compressed air so that the pressure thereof will not be needlessly reduced.

A further object of the invention is to 65 provide control means of this character which may be installed in already existing systems with very little change and at small expense.

To the attainment of the foregoing and 70 other objects and advantages, the invention preferably consists in the arrangement and combination of parts to be hereinafter more fully described and claimed, and illustrated in the accompanying drawings in which: 75

Figure 1 is a diagrammatic side elevation of a locomotive equipped with sanding mechanism and control means of the present invention,

Figure 2 is an elevation of the control 80 valve on a larger scale, showing the piping arrangement,

Figure 3 is a side elevation of the valve taken at right angles to Figure 2, and

Figure 4 is a sectional view through one 85 portion of the valve.

Referring to the drawings in detail, the numeral 1 designates a boiler of a locomotive having the usual sand dome 2 and 3 represents the cab. The numerals 4 and 5 90 designate sand traps of any ordinary or preferred type supplied with sand by pipes 6 leading from the dome. The outlets from these traps 4 and 5 have connected therewith pipes 7 and 8, the former of which 95 discharges at a point in advance of the forward driver and the latter of which discharges at a point in advance of one of the intermediate drivers. These traps are operated by compressed air brought from a 100 suitable source through a pipe 9 to the inlet 10 of the control valve structure designated generally at 11.

The valve structure is of the duplex type such as is illustrated in Patent No. 1,409,538 105 and is provided with outlets 12 and 13 with which are connected pipes 14 and 15 leading respectively to the inlets of the traps 5 and 4. The valve is further provided with other outlets 16 and 17 from which lead pipes 18 110

and 19 respectively connected with the cleaning nozzles of the traps 5 and 4. The traps and discharge pipes leading therefrom are of course duplicated at opposite sides of the locomotive and connected with the pipes 14, 15, 18 and 19 are pipes 20, 21, 22 and 23 which connect with the corresponding pipes on the other side.

As stated above the valve is of the duplex type and both sides or sections 24 thereof are similar. Between the intake port and between the outlets is formed a valve seat 25 normally closed by a valve 26 carried by a stem 27 and urged into closed position by a spring 28. The valve stem also carries a piston 29 terminating in a plunger 30 which projects beyond the top of the valve. Each section 24 has a bore 31 therein extending from the valve seat 25 to a point near the upper end and leading into or communicating with a chamber 32 located opposite and in communication with the outlet to the cleaner pipes. Suitably pivoted on the valve, as shown at 33, is a handle 34 preferably equipped with a latch device 35 and having laterally extending arms 36 which engage the plungers 30, the construction being such that when the handle is swung in one direction or the other one plunger will be depressed for initially opening the valve 26 to a slight extent so that air will pass from the inlet through the bore 31 into both outlets so that the cleaning action will be accomplished. As the movement is continued the valve 26 is opened farther while the plunger 29 passes into the lower portion of the bore 31 for cutting off the air supply to the cleaners. This detailed action is well disclosed in Patent No. 1,409,538.

All the above described structure is disclosed in the prior patents mentioned and no novelty is claimed therefor though the parts are described and illustrated in order to give a clear explanation of the present invention which consists in or comprises the provision of a pipe 37 connecting the pipes 14 and 15 and having interposed therein a check valve 38. A similar pipe 39 connects the pipes 18 and 19 and has interposed therein a similar check valve 40, the exact location of the pipes and the particular type of valves being immaterial.

With this arrangement it will be seen that when the operating handle 34 is pulled backwardly air will pass into and through the pipes 15 and 18 to the sanders and cleaners, though only momentarily through the latter. The check valves 38 and 40 will prevent the air from passing through the pipes 37 and 39 and it will be observed that as a consequence only the forward sand trap 4 at each side of the locomotive will be operated and sand discharged only in advance of the first set of drivers. By pushing the handle forwardly, or in the opposite direction, the valve

members in the other section of the valve structure will be operated so that air will pass into and through the pipes 14 and 19 and of course to the rear sanders 5. However, as the pipes 37 and 39 connect the pipes 15 and 14, and 19 and 18, respectively, and as the check valves are open to pressure in this direction the air will pass into the pipes 15 and 18 for operating the forward sanders as well as the rear ones so that sand will be discharged in advance of two sets of drivers. It is therefore a simple matter for the engineer to control the sanding action in accordance with the needs which may exist under different circumstances. Obviously the direction of opening of the check valves may be reversed as there is no limitation in this respect.

From the foregoing description and a study of the drawings it will be seen that I have thus provided an extremely simple arrangement for the purpose specified and one in which installation may be made without involving any material changes in existing apparatus. The device will economize in the consumption of sand and will also avoid unnecessary use of compressed air so that the pressure of the supply will not be needlessly reduced.

While I have shown and described the invention as applied to a certain sanding system involving a particular type of control valve means it should be understood that this disclosure is merely illustrative as the right is reserved to make various changes in the construction and arrangement of parts as will adapt the invention for use in connection with other apparatus or mechanisms, provided the variations and modifications constitute no departure from the spirit of the invention or the scope of the claims hereunto appended.

Having thus described the invention, I claim:

1. In a locomotive sanding mechanism including a sand dome, a plurality of sets of sand traps connected with the dome and having respective discharge pipes leading to different sets of drivers, fluid pressure conducting pipes connected with the respective sets of traps, control valves for the respective pipes located within the cab, and a single control means for the valves for admitting fluid pressure selectively to one or all the sets of pipes.

2. In a locomotive sanding apparatus including a sand dome, a plurality of sets of sand traps connected therewith, discharge pipes leading from the sand traps, the pipes from the different sets leading to different pairs of drivers, fluid pressure conducting pipes leading to the respective sets of traps, control valves interposed between a source of fluid pressure supply and said fluid pressure conducting pipes, and check valved connec-

tions between said fluid pressure conducting pipes.

3. In a locomotive sanding mechanism including a sand dome, sets of sand traps connected therewith and having respective discharge pipes leading to different pairs of drivers, fluid pressure conducting pipes connected with the traps, a source of fluid pressure supply, selectively operable control valves interposed between the source of supply and the fluid pressure conducting pipes, the combination with said fluid pressure conducting pipes, of pipes connecting the same and having check valves interposed therein, whereupon actuation of one valve will permit fluid pressure to pass to one set of fluid pressure conducting pipes and operation of the other valve will permit fluid pressure to pass into a plurality for selectively sanding one or more pairs of drivers.
4. In a locomotive sanding mechanism including a sand dome, sets of sand traps connected therewith and having respective discharge pipes leading to different pairs of drivers, fluid pressure conducting pipes connected with the traps, a source of fluid pressure supply, selectively operable control valves interposed between the source of supply and the fluid pressure conducting pipes, the sand traps having cleaning means, and cleaning pipes leading from said valves to the cleaning means, check valved pipes connecting said fluid pressure conducting pipes,

and other check valved pipes connecting said cleaner pipes, whereby upon operating 35 a selected valve fluid pressure may be admitted selectively to the fluid pressure conducting pipes and cleaning pipes of one set of traps or to a plurality thereof.

5. In a locomotive sanding mechanism including a sand dome, a plurality of sets of sand traps connected with the dome and having respective discharge pipes leading to different sets of drivers, fluid pressure conducting pipes and cleaning pipes connected 45 with the respective sets of traps, and valve means located in the cab for admitting fluid pressure selectively to one set of fluid pressure conducting pipes and corresponding cleaning pipes or to all thereof. 50

6. In a locomotive sanding apparatus including a sand dome, a plurality of sets of sand traps connected therewith, discharge pipes leading from the sand traps, the pipes from the different sets leading to different 55 pairs of drivers, fluid pressure conducting pipes leading to the respective sets of traps, control valves interposed between a source of fluid pressure supply and said fluid pressure conducting pipes, and means connecting 60 said fluid pressure conducting pipes for permitting flow of fluid pressure through both thereof in one direction and preventing flow through one in the opposite direction.

In testimony whereof I affix my signature.
WILLIAM H. WHITE.
